UNITED STATES PATENT OFFICE.

HENRY B. NICHOLS, OF PHILADELPHIA, PENNSYLVANIA.

METHOD OF GRINDING AND SURFACING.

961,523.

Specification of Letters Patent. Patented June 14, 1910.

Original application filed September 5, 1908, Serial No. 451,875. Divided and this application filed July 22, 1909. Serial No. 508,941.

To all whom it may concern:

Be it known that I, HENRY B. NICHOLS, a citizen of the United States, residing at Philadelphia, in the county of Philadelphia and State of Pennsylvania, have invented certain new and useful Improvements in Methods of Grinding and Surfacing, of which the following is a specification, reference being had therein to the accompanying drawing.

My invention relates to methods of metal working and especially to methods of grinding.

It has for its object the provision of an improved method for accurately grinding plane surfaces with particular reference to the surface of railway rails.

My present method may be practiced with divers forms of apparatus, some of them automatic and others hand-operated, but I prefer to practice it with my improved grinding machine which forms the subject matter of Patent No. 944,902 December 28, 1909, of which the present case is a division.

Briefly stated, my invention contemplates the continuous removal of a predetermined amount of material from the work at each cut, maintaining this cut constant by causing the amount of motion or the position of the cutting means as determined by the amount of material removed at each portion of the cut to regulate the next portion of the cut.

The machine forming the subject matter of the parent application, and with which I prefer to practice the present invention, is illustrated in the accompanying drawings in which—

Figure 1 is an end view partly in section. Fig. 2 is an opposite end view, with parts removed. Fig. 3 is a side view looking in the direction of the arrow in Fig. 1. Fig. 4 is a plan view. Fig. 5 is a side view of heel and bracket detached from the machine. Fig. 6 is a side view of the complete machine showing pedestal and bridge, with parts mounted thereon. Fig. 7 is an end elevation of the same. Figs. 8 and 9 are detail figures showing a caliper with other parts removed.

It has already been stated that the principles involved in this invention are capable of embodiment in divers forms, and such embodiments are applicable to divers purposes. I believe the idea of automatic cali-

pering so as to regulate the cut in a machine is original with me, and while I have heretofore described and claimed the same as applied to the surface of the work, I present herein for the first time automatic caliper means applied to the tool. In the present state of the art, which in this respect is passing through a transition period, grinding processes are being substituted for so-called cutting, or steel tool processes in many cases. It has come to be recognized that a surface can be ground for a finish with great accuracy, and the rough cuts taken off as well, and in fact that the grinding wheel is neither more or less than a cutting tool which under normal conditions of speed and pressure makes a great number of small cuts and produces correspondingly small chips.

In all precision work where a grinding cutter is employed, compensation must be provided for the wear on the grinding body. This is the prime source of inaccuracy in grinding processes, and to correct it, the ordinary manual adjustment is both clumsy and inefficient. To produce the best results, the cut must be uniformly and continuously regulated, and the means for doing this are applicable to many other forms of metal working machines and cutting tools than those which I shall now describe.

This grinding machine is built in general somewhat after the fashion of the ordinary planer, and it may either have a reciprocating bed, or a traveling tool support or bridge, preferably the former. The frame and other general features of the machine are omitted from the drawings for simplicity, and because they form no direct part of the present invention. The bed of the machine is crossed by a superposed bridge carrying a frame for the grinding wheels and their associated parts; and between the bed and this frame a reciprocating longitudinal feed is provided, which may be of the ordinary screw and traveler type or such other as may be found desirable. In the specific form illustrated, the bed plate carries a rail support, the former being marked 1 and the latter 2. The plate and support reciprocate beneath the superposed frame 3, upon which are mounted a pair of grinding wheels 4 and 5. The rail 6 lies upon the support 2, which is shaped so as to fit into the angle of the tram and web, the latter being hori-

zontal. This projects the head and foot flanges vertically so that their inner faces 7 and 8 may be engaged by the wheels 4 and 5. It has already been explained that the relation of these faces 7 and 8 must be constant as regards both distance and angle, and also that the joint relation of these two faces and the surface 9 on the head 10 must be maintained constant, or, in other words, that the thickness of the head must not vary. To secure these results, and in order to guard against any variation due to the wearing away of the wheels, the latter are made adjustable to and from each other, also in an arc having a large vertical component; and all these adjustments are referred to certain fixed stops or guides which determine a fixed plane in which the surface 9 must rest during grinding. These stops or guides are constructed as brackets 11 and 12, held in T-slots 13 and 14 formed in lugs on the underside of the frame 3. Each bracket is bifurcated as shown at 15, and carries a hardened steel roll 16 journaled on a pin 17. A further adjustment is provided which is never changed during the operation of the machine and is therefore not properly classed with the others. This is the adjustment of the rolls 16 toward and away from the rail-support 2. It is of use when setting up the machine for different shapes or sizes of rails, and for taking up wear on the rolls and pins. It is accomplished through the agency of shouldered feed screws 18 and 19, whose shoulders lie upon opposite sides of projecting abutments on the frame, and whose threaded stems engage the brackets 11 and 12 to move them in the T-slots. For operative purposes these brackets with their rolls may be referred to as the fixed guides, since they, with the support 2 determine the correct position of each rail as it is run through the machine.

It will be observed that the grinding is accomplished by the faces of the wheels, which work against the surfaces 7 and 8 in opposite directions. Edge grinding on the same wheels, and also grinding on the inner faces may be resorted to, but in grinding rails as shown the wear will all be on the outer faces, *i. e.*, those which lie away from each other. To compensate for this wear feed screws 21 and 22 are provided, carried in overhanging brackets 23 and 24 and acting upon the wheels through travelers 25 and 26; and in order to permit of the automatic control of these feed screws in response to wear on the wheel, a peculiar construction of the latter is resorted to which I will now describe.

Fig. 1 shows the wheels edge on, the dotted lines indicating their sectional formation, while Fig. 5 shows one wheel bracket or frame 28 removed, and the wheel with

its face exposed. The body of the wheel is formed of abrasive material such as carborundum or the like, properly shaped and with suitable fittings to secure it to the spindle 29 or 30. As it would be impracticable to apply the automatic calipers directly to the surface of this abrasive material, I provide inserts in the shape of annular bodies of anti-friction or lubricant material at 31 and 32. The best material for this purpose which I have found up to the present time is graphite molded into channels or grooves in the wheels. 70

The two wheels 4 and 5 are uniform, although of course reversed as to their mountings, and a description of one will therefore suffice for both. The bracket 28 is U-shape, with spindle bearings in the extremities 33 and 34 of its arms or bifurcations, and a stem or trunnion 36 fitted to bearings 37 85 formed on the frame 3, and shouldered at 38 to prevent end play. Each bracket may thus be turned in the bearings 37, in order to change the angle of the wheel spindle 29 or 30 and therefore of the face of the wheel, 90 relatively to the frame 3. This angular motion is limited and the adjustment held by means of a slotted arm 39 on the outer end of the trunnion which is bolted at 40 to a lug 41 on the frame 3. The outer arm of the 95 bracket 28 has an upstanding extension 35 cast upon it, both this and the U-arms being flanged to secure rigidity, and the upper end of the arm 35 carrying the overhang 24 and feed screw 22, together with a solenoid 42 100 and a ratchet mechanism actuated thereby for turning the feed screw. For the purpose of setting up the machine and preliminary adjustment the screw 22 has a squared head 43 outside of the arm 35. 105

The solenoid and ratchet mechanism are best shown in Fig. 5. The ratchet wheel 44 is fixed upon the feed screw, and co-operating with it is a pawl 45 pivoted at 46 on a rocker plate which turns on the stem of the 110 screw, so the device is self-centering. The plate 47 is pivotally connected at 48 to the plunger 49 of the solenoid 42 (for which any desired type of electromagnet can be substituted) and the pawl is kept normally 115 retracted by means of a spring 50. When the solenoid is energized its core or plunger is drawn in and the plate 47 is turned to the left in Fig. 5, causing the pawl to turn the ratchet and with it the feed screw 22. 120

The traveler or nut 26 carries an arm 51 which extends down and engages a collar fixed on the grinding head or the spindle, preferably the former. If the former, then the bushing of the head or wheel is splined 125 on the spindle, and if the latter, the spindle must have end play in its bearings. As the screw 22 turns, the nut 26 and arm 51 are shifted, the latter carrying with it the grinding head, which moves in the direction of its 130

axis, or on lines normal to the surface 7 or 8, thus maintaining the angle of the cut constant, while compensating for wear.

The adjustment thus described could of course be brought about manually, but one of my principal objects is to make this automatic, and dependent upon as well as proportionate to the actual wear on the surface of the wheel. This object is attained by the use of the automatic calipers, which will now be described. The two spindles 29 and 30 are driven by belts 52 and 53 taking over pulleys 54 and 55 secured upon the spindles intermediate of the U-arms of the respective brackets 27 and 28. For the sake of uniformity in grinding, both belts preferably derive their power from the same countershaft, which is not shown but which may be either above or to the rear of the machine. One of the spindles 30 carries a pulley 56 outside of its bearing, from which a belt 57 passes to the pulley 58 of the caliper mechanism. The latter is mounted on a rearward extension 3^a of the frame 3, and comprises the caliper levers 59 and 60 pivoted at 61 and 62, provided with rearwardly extending contact arms 63 and 64 and periodically actuated by a double reciprocating slide bar 65, 66, having an intermediate cam frame 67 and driven through a worm wheel from the spindle 68 and pulley 58. It should be noted that the driving pulleys of the spindles 29 and 30 are preferably connected thereto with a universal motion, so that their axes will remain parallel to the countershaft for all angular adjustments of the spindles, their centers at the same time remaining fixed, each in the axis prolonged of its trunnion 36, so there is no variation in the tension of the belts. A similar effect may be produced by giving these pulleys approximately spherical surfaces, or curving them on the centers. In order to avoid excessive twisting of the belt 57, the driving spindle 68 of the caliper mechanism is permanently set at an angle so that its axis will be parallel to the axis of the spindle 30, from which it is driven when the latter spindle is in its normal or intermediate position, equidistant from both extremities of its angular path of travel. By this means the planes of the pulleys 56 and 58 diverge from each other by only one-half the total angle of adjustment of the spindle 30, through its entire range. The angular setting of the spindle 68 is well illustrated in Fig. 2 which, as already stated, is a view looking in the direction of the arrow 2^a in Fig. 4.

The worm 69 drives the wheel 70, which turns a short stub shaft 71 journaled on the frame 3^a. This stub shaft in turn communicates motion through miter gears 72 to an upstanding shaft 73 carrying a cam 74 which as it rotates impinges on one and then the other of the cam projections 75, 76 formed

on opposite sides of the frame 67, thus throwing the frame alternately in opposite directions and carrying with it the slide bars 65, 66. On the ends of these bars are collars 80 and 81, secured by set screws 82 and 83 and provided with depending fingers 84, 85 (see Fig. 2), the lower ends of which engage between flanges on the collars 86 and 87 fitted to slide upon the fixed bar 88, mounted below and parallel to the double bar 65 and 66. Thus, as the upper bar is reciprocated by the double or actuating cams, the collars move with it, and in so moving them advance their associated calipers one at a time into engagement with the surface of the wheel, and if the latter is worn so that the line of cut is below normal, the particular caliper in contact will become advanced far enough for the tail of its lever 63 or 64 to close contact at 89 or 90 as the case may be and thereby to affect the feed mechanism of the worn wheel.

The structure and detailed arrangement of the caliper levers is best shown in Figs. 8 and 9, which are detail views with the other parts removed. Each lever is in three parts, the body 91, the forwardly extending arm 92 and the rearwardly extending contact arm 93. The body is in the form of a sleeve sliding upon bar 88, and engaged by two coiled springs 95 and 96, the former resting against the collar 86 and the latter against an extension of the frame carrying the bearing for the shafts. These springs are normally adjusted so that the body or sleeve will remain in an intermediate position with their caliper or feeler out of contact with the wheel, as shown in Fig. 4. The lever 93 is pivoted at 93^a upon a rigid bracket projecting from the bearing portion of the frame. This pivot point is so located as to leave a long contact arm, and a relatively short actuating arm, connection of the latter with the body being effected by means of a pivot 93^b. Thus, as the body reciprocates on the bar 88, the lever 93 is turned upon the pivot 93^a.

The arm 92 carries "feelers" shown in the form of steel rollers 99, adapted to touch the graphited rings in the face of their wheel when the caliper is actuated. These are carried upon a holder, rotatably adjustable in a socket piece 79, and locked when adjusted by means of a set-screw 101. This socket piece has a vertical adjustment in the holder or yoke 92^c, this being regulated by the screws 61 or 62.

The springs 95 and 96 are of such relative strengths, that 96 normally overcomes 95 and forces the body 91 to the left in Figs. 6 and 7. When the collar 86 or 87 is moved however, it compresses its associated spring 95 putting sufficient tension thereon to overcome the spring 96, thereby pushing the body 91 along the bar 88, carrying the feelers or

rollers 99 into contact with their wheel, and at the same time turning the lever 93 on its pivot 93^M. It will be observed that while the movement is positive, the connections are all resilient, so that no fine adjustments are required in these connections between the cam frame, the sliding bars and the calipers. The rollers 99 are held when adjusted upon the holder 60 by means of lock-nuts 100, and of course the rotation of this holder in its sleeve together with the vertical adjustment of the sleeve or socket permits the adaptation of the rollers to any position of the wheel 4 or 5.

5 Electrical connection is effected with each caliper lever by means of a binding post 97, and the terminal contacts 89 and 90 are associated with insulated fixed terminals 98. These terminals 97 and 98 are connected in a 0 circuit which includes a suitable source of current and the windings of the solenoid 42. Upon the closure of the contacts by either 5 caliper, its solenoid will become energized, and will thereupon advance its wheel in the manner hereinbefore described.

It will be noted that the stub shaft 73 is not exactly vertical but is perpendicular to the spindle 68. It will appear from Fig. 2 that the cam surfaces are correspondingly 0 inclined, bringing the points of impact of the cam 74 on the teeth 75 and 76 to the upper part of one and the lower part of the other, the frame 67 being broad enough to permit this. It is thought the operation of 5 the machine will be sufficiently apparent from the description without any detailed statement thereof. As a brief recapitulation however, it may be stated that when a rail is to be ground, the machine is first set 0 up with all the parts adjusted substantially as shown in the accompanying drawings. The rail is then introduced, and the main feed mechanism with its stops set so as to produce the length of cut desired. The 5 wheels 4 and 5 being rotated through to driving pulleys, produce cuts of a predetermined depth, and at predetermined angles in the head and foot flanges. The calipers are periodically brought into action in the 0 manner heretofore pointed out, and as long as the wheel surfaces are not worn to a greater extent than the maximum variation permitted and predetermined in the work, the feed is not affected. As soon as the 5 wheel surfaces wear however, to an amount

exceeding the predetermined limit, each caliper will close its contacts 89 or 90, energizing its respective solenoid, and step around its feed screw 21 or 22 so as to move the wheel and its sleeve or bushing upon the 60 spindle and compensate for the wear. In this manner, and by properly constructing and adjusting the calipers, the cut on a rail or any other surface produced in this machine can be kept within a percentage variation so small as to be practically negligible. 65

When the machine is to be used for other work than railway rails, the support 2, the guides or stops, and other parts, will be altered or adjusted accordingly. The wheels 70 4 and 5 may be reversed in their action so as to grind on their inner instead of their outer faces; and thus it is possible to pass an object between the two wheels, and grind both its outside faces simultaneously, each at 75 a different angle if so desired. In addition to thus varying the uses of this specific machine, the wheel parts and driving mechanism may be changed, remodeled or redesigned for any desired class of work, and 80 this without departing from my invention if the main principle is still employed, which is to maintain a constant cut by causing the cutting surface to affect mechanism which will automatically and continuously compensate for wear. Obviously, this principle 85 may be embodied in machines employing edge cutting instead of face cutting wheels, or in metal working machines employing steel cutting tools instead of abrasives. All 90 such variations are contemplated by me, and are to be considered as well within the scope of the appended claim.

Having thus described my invention what I claim and desire to secure by Letters Patent is—

In metal work, the method of producing a uniform cut unaffected by wear of the cutting tool, which consists in causing variations or changes in the surface of the cutting 100 tool during the progress of the cut to immediately react so as to produce a compensating relative adjustment between the tool and work, without interrupting the cut.

In testimony whereof I affix my signature 105 in presence of two witnesses.

HENRY B. NICHOLS.
